UNITED STATES PATENT OFFICE.

CHARLES HULTGREN, OF CHICAGO, ILLINOIS, ASSIGNOR TO S. KARPEN & BROS., OF CHICAGO, ILLINOIS, A CORPORATION OF WEST VIRGINIA.

MACHINE FOR SERVING TACKS, NAILS, ETC.

Application filed February 12, 1925. Serial No. 8,724.

This invention relates particularly to a machine adapted to the purpose of receiving tacks, nails, or the like, and serving them out for use, as required.

5 Such a machine may be usefully employed, for example, in factories engaged in the manufacture of upholstered furniture. In such factories, it is necessary to employ tacks of different sizes, or kinds; and where the tacks 10 are taken from kegs, there is great danger that workmen will throw tacks originally taken from one keg into another keg, and thus destroy the proper assortment.

In accordance with the present invention, 15 a plurality of receptacles are provided, each of which is of suitable size to receive an entire keg of nails. These receptacles may be kept locked, so that there is no possibility of the workmen returning tacks to them and 20 making errors which might result in spoiling the assortment. The receptacles are provided with means for serving or dispensing the tacks to the workmen, as they are required.

The invention is illustrated in its preferred 25 embodiment in the accompanying drawings, in which—

Fig. 1 shows a front elevational view of a machine provided with four independently mounted receptacles; Fig. 2 is an edge elevational view of the same; Fig. 3 is a vertical sectional view of one of the receptacles, taken as indicated at line 3 of Fig. 1; Fig. 4 is a broken longitudinal vertical sectional view taken as indicated at line 4 of Fig. 2; Fig. 5 30 is a plan view of the machine with two of the receptacles removed; Fig. 6 is a vertical sectional view through one of the hoppers, one of these hoppers being disposed beneath each receptacle, the section shown in Fig. 6 being 35 taken as indicated at line 6 of Fig. 5; and Fig. 7 is a detailed sectional view through the discharge spout of one of the hoppers, the section being taken as indicated at line 7 of Fig. 1.

40 In the illustration given, A represents a frame; B represents a series of receptacles journalled in the upper portion of said frame; and C represents a series of stationary hoppers mounted on the frame beneath the 45 receptacles.

The frame A may be of any suitable construction. In the illustration given, it is shown of rectangular form and constructed principally of angle iron. The upper portion 50 of the frame supports a trunnion 1 which

extends between the end-standards 2 of the frame.

The receptacles B are provided in their side-walls near their centers with diametrically opposite openings equipped with reinforcement rings, or bearings, 3. The shaft 1 extends through these bearings, and the receptacles are thus independently journalled on the trunnion 1. Each receptacle preferably is in the form of a cylindrical vessel of sheet-metal, and is equipped with a removable lid 4. The lid is removable, but is secured in position by means of a bar 5 which extends diametrically across the lid and through perforate ears 6 which project upwardly from the vessel. One end of the bar 5 is provided with a lug 5^a, and the other end is provided with a perforation which receives a padlock 5^b.

Each vessel B is provided at its front side, 75 near its upper end, with a discharge opening 7 which opens into a discharge-chute 8 which is secured to the front wall of the vessel. In the discharge chamber 8 is mounted a valve 9 which is secured to a shaft 10 which projects through the lateral walls of the chamber 8. One end of the shaft 10 is equipped with a 80 actuating lever 11 which is connected by a spring 12 with the body of the vessel B. The spring serves to hold the valve 9 normally in a position to close the passage 85 through the chamber 8. The lower end of the chamber 8 is provided with a funnel-shaped discharge portion 8^a. The lid of the vessel B is equipped with a handle 13.

The hoppers C have their upper ends secured to longitudinal bars 14 constituting part of the frame A. These hoppers are open at their upper ends, and project some distance in front of the vessels B. The hoppers 95 have forwardly and downwardly inclined bottoms 15, and are equipped at their lower front portions with discharge funnels 15^a. Slide valves 16 mounted in suitable guides and equipped at their front ends with handles 100 16^a serve normally to close the upper ends of the funnels 8^a. Springs 17 hold the slide valves 16 normally in the closed position.

In the use of the machine, a keg of tacks, for example, is opened and dumped into each 105 receptacle B. The receptacle is then closed and locked. The receptacles B may be suitably numbered to indicate the sizes of the tacks in the various receptacles. When a workman desires a supply of tacks, he tilts, 110

or rotates, the receptacle B forwardly, thus causing a supply of tacks to be discharged into the upper portion of the front, or auxiliary, chamber 8. He allows the vessel to 5 return to its normal position, and then places a can, or cup, beneath the spout 8^a. He then depresses the lever 11, thus throwing the valve 9 downwardly and permitting the tacks to be discharged into the can, or container, 10 which he employs to receive them. Suitable space is provided above the hoppers C to enable the small container which the workmen carry to be placed in position beneath the spout 8^a. Any overflow of tacks will be 15 caught by the hopper C; and when there is a sufficient accumulation, the slide valve 16 may be opened and the tacks may be caught by a container placed beneath the discharge-funnel 15^a.

20 A device of the character described can be manufactured at moderate cost, and affords an exceedingly handy and useful device for the purpose set forth.

It may be added that the center of gravity 25 of the vessel B is somewhat below the trunnion 1, so that the vessel normally will as-

sume an upright position. The vessel may be rotated in a forward direction to a completely inverted position, if necessary, to enable the contents to be discharged through 30 the opening 7.

The foregoing detailed description has been given for clearness of understanding only, and no unnecessary limitations should be understood therefrom, but the appended 35 claim should be construed as broadly as permissible, in view of the prior art.

What I regard as new, and desire to secure by Letters Patent, is:

In a machine of the character set forth, 40 the combination of a frame, a series of stationary hoppers mounted in the lower portion of said frame, a trunnion extending horizontally over said hoppers, and a series of vessels having their side walls provided with 45 perforations through which said trunnion extends, said vessels being equipped at their front sides with discharge chutes, having ports at their upper ends communicating with the upper portions of said vessels.

CHARLES HULTGREN.
